UNITED STATES PATENT OFFICE.

AUGUST GERSTNER, OF NEW YORK, N. Y.

DIRIGIBLE BALLOON.

No. 880,070.

Specification of Letters Patent.

Patented Feb. 25, 1908.

Application filed April 30, 1907. Serial No. 371,166.

To all whom it may concern:

Be it known that I, AUGUST GERSTNER, a citizen of the United States, and resident of the borough of Brooklyn, in the city and 5 State of New York, have invented a new and useful Improvement in Dirigible Balloons, of which the following is a specification.

The object of my invention is to provide a balloon which can be readily propelled in any 10 direction, the propelling power being so arranged that the gas-container and the framework suspended therefrom are both propelled through the air so as to obviate all torsional strain on the balloon.

15 A further object is to provide a very simple and effective means for steering the balloon.

In the accompanying drawings, Figure 1 represents the balloon in end elevation, Fig. 20 1^a is a detail view showing the manner of attaching the netting to the framework for suspending the framework from the gas containers, Fig. 2 is a side view of the balloon one of the gas containers being shown partially in longitudinal central section to more 25 clearly show the tube extending therethrough and the series of propellers located in said tube. Fig. 3 is a top plan view of one-half of the framework with the gas containers removed, and Fig. 4 is a top plan view of the 30 other half of the framework with the gas containers removed.

The gas containers are each denoted by 1. There are two of these gas containers shown 35 herein and they are of oval form so as to present the least resistance to the air when the balloon is in use. An open-ended tube 2 extends lengthwise through each gas container. The small ends of each gas container are 40 clamped between plates 3 and 4 at the ends of the tube 2. A framework 5 is suspended from the gas containers by providing nets 6 passing over the upper portions of the containers, the said nets being secured to the 45 upper longitudinal beams of the framework. This framework may be of any desired shape and material to suit different requirements. A series of propellers 7 are fixed to rotary shafts 8 which extend centrally through the 50 tubes 2, the ends of the said shafts being mounted in suitable bearings in cross beams 9 and 10. A motor 11 of any well known and approved form is carried by the framework 5, which motor is used to drive the two 55 series of propellers 7 within the tubes 2 as

follows. A sprocket chain 12 passes around a sprocket wheel 13 on the engine crank shaft 14 and also around a sprocket wheel 15 on a stud shaft 16 mounted on the framework 5 between the gas containers 1. This stud shaft 16 is provided with a sprocket wheel 17. A sprocket chain 18* passes around sprocket wheels 19* fixed to the propeller shafts 8 and also is engaged by the sprocket wheel 17 on the stud shaft 16.

60 The steering apparatus which I have provided is also used for propelling the balloon and is constructed, arranged and operated as follows. A plurality of horizontal swinging open-ended steering tubes 18, in the 70 present instance four of these tubes are shown, are mounted to swing on supports 19 uprising from the bottom of the framework 5. Each one of these tubes 18 is provided with a plurality of propellers 20 fixed to a short 75 rotary shaft 21 mounted in a supporting bracket 22 of the steering tube. Each of these shafts 21 is provided with a bevel gear 23 which meshes with a bevel gear 24 fixed to a rotary vertical shaft 25, mounted in the 80 upright 19. Each one of these bevel gears 24 is rotated from the crank shaft 14 of the motor. In the present instance those two bevel gears 24 nearest to the motor are driven from a cross shaft 26 having a geared connection 27, 28, with the motor shaft, the ends 85 of the said shaft 26 having bevel gears 29 meshing with bevel gears 30 on the shafts 25. The bevel gears 24 of the two steering tubes furthest from the motor are driven through 90 longitudinal shafts 31 which have bevel gears 32 meshing with the bevel gears 29, 30, and also with bevel gears 33 meshing with the bevel gears 34 on the shafts 25 of the bevel gears 24 for the said steering tubes 95 farthest from the motor.

A steering wheel 35 is mounted about centrally of the framework 5, which steering wheel has a pinion 36 which meshes with a rack 37. A steering rope or other flexible 100 connection 38 has its free ends attached to the ends of the rack 37 and passes around pulleys 39, 40, 41, 42 carried by the framework 5. The tiller 43 of each steering tube 18 is attached to the said flexible connection 105 38 so that all of the steering tubes are swung simultaneously in the same direction to any desired position.

In operation, when the motor is started it will start the propellers rotating in the steer- 110

ing tubes and in the gas containers. This will cause the air to be sucked through the tubes and thereby draw the balloon ahead. The shifting of the weight of the occupant of the balloon will cause the balloon to be propelled upwardly or downwardly or horizontally as may be desired. The shifting of the direction of the movement of the balloon may be accomplished by turning the steering wheel to swing the steering device.

It will be seen that a balloon constructed according to the principles herein set forth will be arranged so that the gas containers and the framework are both propelled, thus eliminating the strain on the balloon incident to propelling the balloon by apparatus arranged either in line with the gas container or in line with the framework, as has heretofore been common. It will furthermore be seen that the rotary movement of the propellers in the steering tubes is not interfered with by the swinging of the steering tubes into their different positions.

It is evident that various changes might be resorted to in the construction, form and arrangement of the several parts without departing from the spirit and scope of my invention; hence I do not wish to limit myself strictly to the construction herein set forth, but

What I claim is:

1. In a dirigible balloon, a plurality of gas containers, a framework suspended therefrom, longitudinal open ended tubes centrally arranged in the gas containers, a plurality of propelling devices for the containers situated in said tubes, a propelling device for the framework and a common motor for all the propelling devices.

2. In a dirigible balloon, a plurality of gas containers, a framework suspended therefrom, longitudinal open ended tubes centrally arranged in the gas containers, a plurality of propelling devices for the containers situated in said tubes, a plurality of propelling devices for the frame and a common motor for all the propelling devices.

3. In a dirigible balloon, a plurality of gas containers, a framework suspended therefrom, longitudinal open ended tubes centrally arranged in the gas containers, a plurality of propelling devices for the containers situated in said tubes, a combined propelling and steering device for the frame and a common motor for all the propelling devices.

4. In a dirigible balloon, a plurality of gas containers, a framework suspended therefrom, longitudinal open ended tubes centrally arranged in the gas containers, a plurality of propelling devices for the containers situated in said tubes, a plurality of combined propelling and steering devices for the

frame and a common motor for all the propelling devices.

5. In a dirigible balloon, a plurality of gas containers a framework suspended therefrom, longitudinal open ended tubes centrally arranged in the gas containers, a plurality of propelling devices for the containers situated in said tubes, a combined propelling and steering device consisting of a radially swinging tube and a propeller situated therein, said tube being fastened to the frame and arranged to swing in a plane parallel thereto and a common motor for all of the propelling devices.

6. In a dirigible balloon, a plurality of gas containers, a framework suspended therefrom, longitudinal open ended tubes centrally arranged in the gas containers, a plurality of propelling devices for the containers situated in said tubes, a plurality of combined propelling and steering devices, each consisting of a radially swinging tube and a plurality of propellers situated therein, said tube being fastened to the frame and arranged to swing in a plane parallel thereto, and a common motor for all of the propelling devices.

7. In a dirigible balloon, a plurality of gas containers, a framework suspended therefrom, longitudinal open ended tubes centrally arranged in the gas containers, a plurality of propelling devices for the containers situated in said tubes, a plurality of combined propelling and steering devices consisting of a plurality of radially swinging tubes, a propeller situated in each of said tubes, said tubes being fastened to the frame and arranged to swing in a plane parallel thereto, and a common motor for all of the propelling devices.

8. In a dirigible balloon, a plurality of gas containers, a framework suspended therefrom, longitudinal open ended tubes centrally arranged in the gas containers, a plurality of propelling devices for the containers situated in said tubes, a plurality of combined propelling and steering devices consisting of a plurality of radially swinging tubes, a plurality of propellers situated in each of said tubes, said tubes being fastened to the frame and arranged to swing in a plane parallel thereto, and a common motor for all of the propelling devices.

In testimony, that I claim the foregoing as my invention, I have signed my name in presence of two witnesses, this twenty-seventh day of April 1907.

AUGUST GERSTNER.
